(57) **CLAIM**

The ornamental design for a hex shank tap as shown and described.

DESCRIPTION

FIG. 1 is a perspective view of a hex shank tap in accordance with a first embodiment of my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a hex shank tap in accordance with a second embodiment of my new design;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of a hex shank tap in accordance with a third embodiment of my new design;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The broken lines in FIGS. 1-21 illustrate portions of the hex shank tap that form no part of the claimed design. The dot-dash broken lines in FIGS. 8-12 and 15-19 represent unclaimed boundary and forms no part of the claimed design.

1 Claim, 12 Drawing Sheets
